F. GALL

HAND MEMBER FOR DIVING ARMORS

Filed Aug. 31, 1921

Inventor:
Friedrich Gall

UNITED STATES PATENT OFFICE.

FRIEDRICH GALL, OF KIEL, GERMANY.

HAND MEMBER FOR DIVING ARMORS.

Application filed August 31, 1921. Serial No. 497,427.

To all whom it may concern:

Be it known that I, FRIEDRICH GALL, citizen of the German Republic, and residing at Kiel, county of Schleswig-Holstein, State of 5
Prussia, Germany, have invented certain new and useful Improvements in Hand Members for Diving Armors (namely, for which I have filed application in Germany, March 2nd, 1917, No. 334,693; Belgium, 10 June 7th, 1920, No. 287,401; Sweden, April 20th, 1920, No. 53,927; Holland, May 3rd, 1920, not yet granted; Denmark, May 26th, 1920, No. 27,687; Norway, June 1st, 1920, No. 34,170; England, July 10th, 1920, No. 15 148,434; Italy, June 29th, 1920, No. 536/136), of which the following is a specification.

The hand-members employed hitherto for divers' armors were, in regard to their external shape and mode of operation in seizing things, more or less similar to the human hand. But cases may arise in which these armor hands do not meet the requirements to be fulfilled in performing certain work. As diving armors are used in very deep 25 water, and the pressure in their interior is only that of the atmosphere, the hydrostatic pressure at the articulations causes the different members to be pressed against each with great force. When the members are 30 moved this pressure engenders great friction, which greatly diminishes the force that can be exerted by the hand on external objects and accelerates fatigue. This drawback renders it almost impossible for the 35 diver to handle tools properly at great depths.

The known diving armors in which hand members are dispensed with, and in which a hook is passed through a stuffing box at 40 the extremity of the arm member, or in which this member is provided with a tool similar to a pair of pliers or tongs that can be manipulated from within, do not permit of the tools being employed as if they were 45 operated by the human hand. Hence as instruments for the execution of work under water they are very imperfect.

By the present invention these drawbacks are removed and the diver is enabled to use 50 his sense of feeling in operating with, and handling, his tools.

This is accomplished by constructing the hand-member in the form of an artificial articulation and by providing it with a handle 55 to which the tool to be used can be firmly fixed and that is mounted in a movable joint

and can be operated in the interior of the member. A simple form of such a handle consists of a narrow sleeve or tube which is fixed at its front open end in a ball socket or 60 articulation arranged in the hand member and whose inner end, that extends into the said member, is closed. To enable tools having a plurality of movable parts, such as a pair of pliers, of which only one limb can 65 be inserted in the handle, to be operated by the aid of the hand member, guide members which act as stops for checking the movement of one of the said parts are provided on the exterior of the hand member. To 70 enable the greatest possible force to be exerted a hold towards which the handle is moved is provided in the interior of the hand member for the diver's hand.

The invention is illustrated in the drawing in which a constructional form of the novel device, together with a pair of tongs, is shown.

The hand member consists of a casing *a*, in the interior of which the hand can be 80 moved freely, and which is connected at *b* to the arm member. The casing *a* is formed with a tapering projection *a*₁, at the extremity of which there is a ball-and-socket joint *d*, that serves as a pivot for the handle *c*. Inserted in the handle *c*, whose longitudinal axis is inclined to the axis of the arm member at an angle corresponding to the natural position of the fingers of a closed fist, is the limb *i* of a pair of pliers *e*, whose 85 other limb *k* is held or guided by an eye *f*, that checks the movement of this limb. The pair of pliers is held in position by a spring detent *g* that cooperates with a corresponding notch in the limb *i*. The jaws of the 90 pliers are automatically kept apart by means of a pressure spring *n* that presses against the limb *k*. A hold for the hand is provided in the interior of the hand-member, and by grasping this hold and the handle at the 95 same time, the diver is able to apply the 100 full closing force of his fist to the tool.

I claim:

1. A hand member for diving armors comprising, a rigid casing, an articulation in 105 the said casing, a handle fixed in the moving member of the said articulation and adapted to be handled in the interior of the casing, and means for fixing a tool in the said handle.

2. A hand member for diving armors comprising, a rigid casing, an articulation in 110

- the said casing, a handle consisting of a sleeve with an open end fixed in the movable member of the articulation and a closed end extending into the casing, and means 5 for fixing a tool in the said sleeve.
3. In combination with the arm member of a diving armor, a hand member comprising a rigid casing, an articulation in the said casing, a handle consisting of a sleeve with 10 an open end fixed in the movable member of the said articulation and a closed end extending into the casing, and means for fixing a tool in the said sleeve, the longitudinal axis of the sleeve forming an angle 15 with the axis of the said arm member.
4. In combination with the arm member of a diving armor, a hand member comprising a rigid casing, an articulation in the said casing, a handle consisting of a sleeve with 20 an open end fixed in the movable member of the said articulation and a closed end extending into the casing, tool holding means on the exterior of the hand member, and 25

means for fixing a tool in the said sleeve, the longitudinal axis of the said sleeve forming an angle with the axis of the said arm member. 25

5. In combination with the arm member of a diving armor, a hand member comprising a rigid casing, an articulation in the said casing, a handle consisting of a sleeve with 30 an open end fixed in the movable member of the said articulation and a closed end extending into the casing, a hand-hold in the casing, tool holding means on the exterior 35 of the hand member, and means for fixing a tool in the said sleeve, the longitudinal axis of the said sleeve forming an angle with the axis of the said arm member.

In testimony whereof I affix my signature 40 in presence of two witnesses.

FRIEDRICH GALL.
